UNITED STATES PATENT OFFICE.

MILLARD F. RICHARDSON, OF KALAMAZOO, MICHIGAN, ASSIGNOR TO THE RIVERSIDE FOUNDRY COMPANY, OF KALAMAZOO, MICHIGAN.

SIPHON FOR WATER-CLOSET TANKS.

No. 904,228.

Specification of Letters Patent.

Patented Nov. 17, 1908.

Application filed February 4, 1907, Serial No. 355,608. Renewed October 9, 1908. Serial No. 456,947.

To all whom it may concern:

Be it known that I, MILLARD F. RICHARDSON, a citizen of the United States, residing in the city and county of Kalamazoo, State 5 of Michigan, have invented certain new and useful Improvements in Siphons for Water-Closet Tanks, of which the following is a specification.

This invention relates to improvements in 10 siphons for water-closet tanks.

The object of this invention is to provide an improved water-closet tank siphon which is very economical to produce and at the same time one which is desirable and durable 15 in construction with improved detachable guide for the valve lift rod or stem.

I accomplish the object of my invention by the devices and means described in the following specification.

20 The invention is clearly defined and pointed out in the claims.

A structure embodying the features of my invention is clearly illustrated in the accompanying drawing, forming a part of this 25 specification, in which,

Figure 1 is a perspective view of my improved water closet tank siphon, a portion of the valve being broken away. Fig. 2 is a detail vertical section through the valve 30 seat. Fig. 3 is a detail section, taken on a line corresponding to line 4—4 of Fig. 1, the valve lift rod or stem being removed from the guide therefor.

In the drawing, similar reference characters 35 refer to similar parts throughout the several views.

Referring to the drawing, my improved siphon consists of a body or gooseneck portion 1, having a laterally projecting discharge arm at its lower end, the discharge 40 arm having preferably a threaded nipple 2 adapted to receive a suitable coupling. Above the nipple 2 is an upwardly opening valve seat 3. The loop of the gooseneck is 45 strengthened by the brace 5. The end 6 of the siphon is cut on an incline to provide a suitable vent as is usual in such structures. On the inside of the gooseneck is a projecting lug 7 having a rectangular vertical hole 50 8 therethrough adapted to receive the down-turned end 10 of the lift rod guide arm 9.

The parts above described with the exception of the lift guide arm are all cast in one piece. The lift guide arm is provided with a vertical 55 guide-hole 12 therethrough adapted to

receive the lift rod or stem 13 of the valve 14. The valve seats downwardly, as clearly appears from the drawing. As the valve seat is cast integrally with the other parts, and preferably of iron, I preferably provide 60 a seat ring 15 therefor. This seat ring is adapted to fit within the valve seat and forms, in reality, the seat proper, for the valve. The ring 15 is provided with an outwardly projecting flange 16 at its upper edge 65 adapted to rest upon the top of the valve seat when the ring is inserted in position. This ring is suitably secured in position, which, on account of its shape is very easily accomplished. 70

The hole in the lug 7 for the lift rod guide arm is formed so that the guide arm is always held in the proper position. In the accompanying drawing, I illustrate the same as being rectangular in cross section, however, it is evident that it might be greatly varied as long as it is of irregular cross-section to retain the arm positively in position. By thus supporting the lift rod guide arm, I avoid the necessity for clamps for securing the same, and, as stated, it is always held in proper position. Another very great advantage is that it can be removed and inserted by an inexperienced person, no care being required for adjusting the same. 85

My improved siphon is very economical in structure and very durable. By casting the parts in one piece, I avoid the necessity for joints, and consequently expense and likelihood of imperfections. 90

I am well aware that detachable arms have been provided on these siphons with vertical guide-holes for the stems of the ball valves or similar valves which are adjustable and removable by means of set-screws and the like. These require machining and screw-tapping and threading and the insertion of screws. They are very likely to become displaced and are not so effective as the simple castings which I have produced. 100

Having thus described my invention, what I claim as new and desire to secure by Letters Patent is:

1. In a structure of the class described, the combination with a gooseneck or body portion having a laterally extending discharge arm at one end thereof, provided with a downwardly projecting threaded nipple and an upwardly opening valve seat; a lug having a vertical rectangular hole 105 110

therethrough projecting laterally over said discharge arm, the said parts being cast integrally; a valve; a lift rod therefor; and a guide arm for said rod having a downturned 5 rectangular portion adapted to be inserted in said opening in said lug, and a vertical guide-hole at its outer end adapted to receive said lift rod stem whereby said valve is supported and held in alinement with its 10 seat and detachably connected to said body portion.

2. In a structure of the class described, the combination with the body or gooseneck having a laterally projecting integral lug 15 thereon, said lug having a vertical rectangular hole therethrough; a valve; a lift rod or stem therefor; a guide arm therefor having a rectangular downturned inner end adapted to be inserted in said hole in said lug, and 20 a vertical guide-hole at its outer end adapted

to receive said lift rod whereby said valve is detachably supported and held in alinement.

3. In a structure of the class described, the combination with the body or gooseneck having a laterally projecting lug with a vertical hole of irregular cross-section there- 25 through; a valve; a lift rod or stem therefor; a guide arm for said lift rod or stem having a downturned inner end conformed and adapted to be inserted through said hole 30 and a vertical guide-hole in its outer end adapted to receive said rod as specified.

In witness whereof, I have hereunto set my hand and seal in the presence of two witnesses.

MILLARD F. RICHARDSON. [L. S.]
